UNITED STATES PATENT OFFICE.

WILLIAM H. JESSUP, OF SHERIDAN, INDIANA.

CABLE CARRIER.

1,033,902.

Specification of Letters Patent. Patented July 30, 1912.

Application filed July 28, 1911. Serial No. 641,056.

To all whom it may concern:

Be it known that I, WILLIAM H. JESSUP, a citizen of the United States, residing at Sheridan, in the county of Hamilton and State of Indiana, have invented a new and 5 useful Cable Carrier, of which the following is a specification.

This invention relates to an improvement in cable carriers, the primary object of the 10 invention being the provision of a carrying means mounted upon the cable and provided with means whereby a bucket or other conveyer may be retained in a relative position to the carrier and be released automatically therefrom.

A further object of the invention is the provision of a pulley sheave provided with a trigger releasing device operated when the conveyer is pulled upwardly to release said 20 trigger and thereby the conveyer.

With the foregoing and other objects in view which will appear as the description proceeds, the invention resides in the combination and arrangement of parts and in the 25 details of construction hereinafter described and claimed, it being understood that changes in the precise embodiment of invention herein disclosed can be made within the scope of what is claimed without departing 30 from the spirit of the invention.

In the drawings;—Figure 1 is a side elevation showing the carrier with the bucket in its elevated position. Fig. 2 is a front detail view of the pulley sheave and trigger 35 mechanism. Fig. 3 is a side elevation thereof. Fig. 4 is a similar view to Fig. 1 with the bucket or conveyer released.

Referring to the drawings, A designates the cable for hauling or carrying the conveyer, B is the main carrier mounted on the cable A, C is the bucket or conveyer, D is what is termed the haul-out line and E is the line for pulling the bucket backward and for releasing the bottom thereof. The 45 carriage or carrier B supports the pulley sheave 1 by means of the cable F and by this means the bucket or conveyer C may be raised or lowered. The pulley sheave 1 has connected across near its upper end the pin 50 2, which also has connected to it the two vertically arranged strips 3, and pivoted to the said pin 2 between the upper ends of the strips 3 and the pulley sheave, are the trigger releasing devices 4, each one of which 55 consists of the downwardly extending arm having the slotted or curved terminal 5 and

the trigger releasing hook 6. The slot in the curved arm 5 is adapted to slide upon the pin 7 carried by each strip 3, as shown, and to thereby cause the hooks 6 to describe 60 an arc of a circle with the center, the pin 2.

When the parts assume the position as shown in Fig. 1, the hook triggers 8 have their terminals 8' in engagement with the pin 2, said hooks being arranged in pairs 65 and being mounted upon opposite sides of the upper end of the sheave plate 1. In order to hold the triggers or hooks 8 in this position, the coil springs 9 are employed. When it is desired to release the sheave 1 70 from the position shown in Fig. 1 to that shown in Fig. 4, the cable F is pulled upon. This action lifts the sheave, causing the arms 4 to ride upwardly along and against the under side of the terminals 8', this action 75 pushes the triggers 8 outwardly to assume a tension against the springs 9. When the sheave is lifted to its highest point, the terminals 8' of the triggers 8 will engage the hooks 6, so that when the cable F is released 80 to permit the sheave to lower, the trigger releasing devices 4, being held outwardly and they themselves holding the triggers 8 outwardly, as shown in Fig. 3, the sheave will lower and the triggers 8 will be 85 finally released, so that when they are snapped inwardly the pin 2 will be out of the path to be engaged by the said triggers, the parts assuming the position as clearly 90 shown in Fig. 4.

To the lower ends of the strips 3 are connected the links 10 which in turn are connected to the bail or bucket handle 11 of the bucket C. Connected to the end of the cable E is a short lever 12 which in turn is pivoted intermediate of its ends to the upper end of the long link 13 whose lower end is connected at 14 to the pivoted bottom 15 of the bucket C, said bottom 15 being hinged exteriorly of the bucket as at 16, whereby 100 the hinges are not in any way interfered with by the dirt dumped from the bucket. By this construction it will be seen that the cable E can release the bottom of the bucket and dump the contents therefrom and after 105 such releasing that the bucket may be returned to filling position by pulling upon the cable E.

It is therefore evident from the foregoing that a means to relieve the weight of the 110 bucket or conveyer from the main carriage or pulley sheave rope is provided, having

an automatic means for releasing the same when the said rope or cable is pulled upon to raise the pulley sheave.

The line E runs over the guide pulley 17 disposed between the bail 11, the bail lever 12 having its lower ends pivoted at 18 to opposite sides of the bracket, so that as the line E is loosened, the bail lever 12 will move rearwardly pushing the connecting rod 13 10 downwardly to open the bottom 15.

What is claimed is:—

1. The combination with a cable carrier, a receptacle, a cable for flexibly supporting said receptacle from the carrier, a pulley 15 sheave connecting said receptacle to the cable, a pin connected across the upper end of said pulley sheave, a pair of spring actuated arms pivoted to the carriage and having hooked ends normally in engagement 20 with the pin of the sheave, and two hook releasing devices pivoted upon the pin of the sheave and adapted when the receptacle is raised to release the hooks from the pin.

2. The combination with a cable, of a car-

riage mounted thereon, means for pulling the carriage, a receptacle for carrying material supported flexibly from the carriage, means for pulling the receptacle and carriage and for releasing the material from said receptacle, a cable for flexibly connecting the receptacle to the carriage, a pulley sheave through which said cable passes, a pin connected across the upper end of the said pulley sheave, a pair of spring actuated arms pivoted to the carriage and having hooked ends normally in engagement with the pin of the sheave, and two hook-releasing devices pivoted upon the pin of the sheave and adapted when the receptacle is raised to release the hooks from the pin. 35 40

In testimony that I claim the foregoing as my own, I have hereto affixed my signature in the presence of two witnesses.

WILLIAM H. JESSUP.
